John Solary,
INVENTOR

BY *Victor J. Evans*

ATTORNEY

UNITED STATES PATENT OFFICE.

JOHN SOLARY, OF CHICAGO HEIGHTS, ILLINOIS.

DRAWING IMPLEMENT.

Application filed April 14, 1924. Serial No. 706,489.

This invention relates to a drawing implement, the general object of the invention being to provide means for drawing arcs of circles, the radii of which are of such a length as to make it impossible to use the ordinary compasses.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a diagrammatic view showing how the invention is used.

Figure 2 is a longitudinal sectional view through the device.

Figure 3 is a section on line 3—3 of Figure 2.

Figure 4 is a section on line 4—4 of Figure 3.

In these views, 1 indicates a body which is provided with a head 2 and a detachable point 3 which is preferably threaded to the lower end of the body. An arm 4 extends from the body to carry a spring pressed pin 5 which acts to hold the body in upright position when placed on a surface the spring 5' of this pin acting to frictionally hold the pin in its adjusted position. The upper surface of the head is provided with teeth 6 and a shaft 7 passes through the body and is rotatably mounted therein. The shaft is provided with a head 8 which is arranged above the head 2 and has secured thereto a casing 9 which encloses the head 2. A guideway is formed in the head 8 for receiving a rod 10, said rod being provided with the rack teeth 11 for engagement by a toothed wheel 12 arranged on the shaft 13 rotatably mounted in the head 8 and which also carries a toothed wheel 14 which meshes with the teeth 6 on the head 2. The rod 10 has its outer end provided with a pencil receiving hole 15.

It will thus be seen that when the casing 9 is rotated by the user, the shaft 13 will be rotated by means of the wheel 14 engaging the teeth 6 and thus the wheel 12 will be rotated to cause the rod 10 to be moved. Thus by placing the device in the proper

position on a portion of the radius of the circle to be drawn and revolving the casing in an anti-clockwise direction, the bar 10 will be gradually moved outwardly to trace the arc as shown in Figure 1. Thus I have produced simple means for drawing arcs of circles without the real center of the circles being indicated on the drawing board or sheet upon which the drawing is being made.

The device shown in the drawings has its parts so proportioned that the body 1 must be placed midway the ends of the radius line of the circle on which the arc is to be drawn. Then the rod 10 is drawn out far enough to place the pencil in the hole 15 on the end of the radius line. Then by operating the device as above described, the arc will be drawn, as shown in Figure 1. Thus it is only necessary to find the center of the radius line of the circle of the arc to be drawn and place the body 1 thereon with the pencil at the end of the radius line.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a supporting member, a vertically arranged shaft rotatably mounted in the supporting member, a head on the shaft, a pencil carrying bar slidably mounted in the head, a circular rack on the supporting member concentric with the vertical shaft, a horizontal shaft arranged in the head, a toothed wheel on the horizontal shaft engaging the circular rack, a second toothed wheel on the horizontal shaft, a rack on the pencil carrying bar engaged by the second toothed wheel and means for manually rotating the vertical shaft.

2. A device of the class described comprising a supporting member, a vertically arranged shaft rotatably mounted in the supporting member, a head on the shaft, a pencil carrying bar slidably mounted in the head, a circular rack on the supporting member concentric with the vertical shaft, a horizontal shaft arranged in the head, a toothed wheel on the horizontal shaft engaging the circular rack, a second toothed

wheel on the shaft, a rack on the pencil carrying bar engaged by the second toothed wheel, means for manually rotating the vertical shaft, such means comprising a casing connected with the head of the vertical shaft and enclosing the movable parts.

3. A device of the class described comprising a pointed member having a head provided with a circular rack, an arm on the pointed member, a pin carried by the arm, a vertically arranged shaft carried by the said member; a head on the shaft, a

pencil carrying bar slidably mounted in the second mentioned head and having rack teeth thereon, a horizontal shaft carried by the head on the shaft, a toothed wheel on said horizontal shaft meshing with the rack on the pencil bar and a second toothed wheel on the horizontal shaft engaging said circular rack.

In testimony whereof I affix my signature.

JOHN SOLARY.
